(57) **CLAIM**

The ornamental design for a container for formation of surgical slush, as shown.

DESCRIPTION

FIG. 1 is a perspective view of the right side, front side, and top side of a container for formation of surgical slush with a container top showing the new design;

FIG. 2 is a perspective view of the right side, front side, and top side of a container without the container top of FIG. 1;

FIG. 3 is a front side elevational view thereof;

FIG. 4 is a right side elevational view thereof;

FIG. 5 is a left side elevational view thereof; and,

FIG. 6 is a rear side elevational view thereof.

The broken lines are shown for environmental purposes only and form no part of the claimed design.

1 Claim, 4 Drawing Sheets
